DESIGN FOR A SPOON OR SIMILAR ARTICLE

Axel H. Staf, Providence, R. I., assignor to
Gorham Mfg. Co., Providence, R. I.

Application June 20, 1933. Serial No. 48,476

Term of patent 14 years

To all whom it may concern:

Be it known that I, AXEL H. STAF, of Providence, in the county of Providence and State of Rhode Island, a citizen of the United States, have invented a new, original, and ornamental Design for a Spoon or Similar Article, of which the following is a specification, reference being had to the accompanying drawing forming part thereof.

Figure 1 is an obverse view of a spoon showing my new design.

Figure 2 is a reverse view of the same,
Figure 3 is a section on line 3—3 of Figure 1.

I claim:

The ornamental design for a spoon or similar article as shown.

In testimony whereof I have signed my name to this specification.

AXEL H. STAF.
